UNITED STATES PATENT OFFICE.

ALBERT T. VAN ALSTYN, OF GRAND RAPIDS, MICHIGAN.

PAPER RECEPTACLE OR TRAY.

1,398,611.

Specification of Letters Patent. Patented Nov. 29, 1921.

Application filed August 23, 1918. Serial No. 251,048.

To all whom it may concern:

Be it known that I, ALBERT T. VAN ALSTYN, a citizen of the United States, residing at Grand Rapids, in the county of Kent and State of Michigan, have invented certain new and useful Improvements in Paper Receptacles or Trays, of which the following is a specification.

This invention relates to a paper receiving receptacle or tray, and more particularly to one adapted to be slidably mounted on a desk or the like.

Among the objects of my invention is to produce a paper receptacle affording the maximum of convenience to the user and of such nature whereby it may be quickly and easily slid forward into convenient position for use, pushed back out of the way, or entirely removed from the desk as desired; further to slidably mount such receptacle on the upper portion of a desk or the like in such manner that it may be instantly made available for use; further to provide means to prevent the tray or receptacle from being inadvertently slid too far in either a forward or backward direction when being used, and of such nature to permit the same to be entirely and easily removed from its guide-ways when desired; further to provide novel means for quickly and firmly clamping the guide-way of the tray or receptacle in position on the upper portion of the desk or the like; further to make such clamping means adjustable whereby the device may be used in connection with desks of different dimensions; further to provide a desk tray that will be cheap to manufacture and simple and efficacious in operation; and such further objects, advantages and capabilities as will later more fully appear.

My invention further resides in the combination, construction and arrangement of parts illustrated in the accompanying drawings, and while I have shown therein a preferred embodiment of my invention I desire it to be understood that the same is susceptible of modification and change without departing from the spirit of my invention. In the drawings;

Figure 1 shows a perspective view of a desk having my invention applied thereto.

Fig. 2 is a vertical, transverse sectional view taken through my improved sliding tray and the upper portion of the desk.

Fig. 3 is a vertical section at right angles to that shown in Fig. 2.

Fig. 4 is a plan view of my new paper tray partly in section.

Fig. 5 is a perspective view of the body portion of the tray. 60

Fig. 6 is a perspective view of the bottom of the tray.

Fig. 7 is a perspective view of the blank from which the body portion shown in Fig. 5 is formed. 65

Fig. 8 is a perspective view of the blank from which the bottom shown in Fig. 6 is formed.

Fig. 9 shows a longitudinal vertical section through the upper portion of a desk top having mounted thereon a modified form of base portion. 70

Fig. 10 shows this base portion in perspective and removed from the desk top.

Fig. 11 is a fragmentary perspective view 75 of the front end of this base portion with the clamping plate removed.

Fig. 12 shows a perspective view of the clamping plate in position to be inserted into the base portion. 80

Fig. 13 illustrates how my invention may be adapted to a flat top desk.

Referring to the drawings, my improved device comprises the base portion 1 and the sliding tray 2, the former of which is provided at its rear edge with the downwardly extending lip or flange 3 having at its lower edge the inturned portion 4. The base portion 1 is also provided adjacent its forward edge with the downwardly extending resilient tongues 5, which, when the base portion is formed of sheet metal will be stamped from the body portion of the metal as shown in Fig. 4, it being obvious that any desired number of these tongues may be provided. 95 In the form shown in Figs. 2 and 4 the tongues 5 are formed integrally with the body of the base portion; however, in order to permit adjustability whereby the base portion may be applied to desks of different 100 dimensions these tongues 5 may be arranged as illustrated in Figs. 9 to 12 which will be hereinafter more fully described.

The sliding tray 2 when of sheet metal is formed from the two blanks 10 and 11, the former forming the bottom and the latter the sides. The blank 11 as seen in Fig. 7 is provided with the short slots 12 and the curved ends 13, and by bending this blank along vertical lines at the slots 12 it will be 110 brought into the form shown in Fig. 5, in which it will be seen the metal blank 11 is

also bent along the dotted line 14 to form the outwardly extending flanges 15 at the bottom of the vertical walls 16. The blank 10 is then applied to the bottom of the body 5 portion just described and the edges 17 are bent upwardly and inwardly over the flanges 15 in which position they may be secured by swaging or otherwise, as desired. This 10 results in a simple and easily formed basket possessing great rigidity as well as lightness in weight.

The base portion 1 is formed by bending its longitudinal side edges upwardly as shown at 20 and inwardly as shown at 21 15 (see Fig. 3) thus forming the interior guide-ways 22 within which are adapted to slide the longitudinal edge portions 23 of the bottom of the tray, which are in effect in the completed tray outwardly extending 20 flanges around its lower edge.

From the above description it will be seen that the base portion 1 may be quickly applied to the top of a desk as illustrated in Fig. 2 and the tray slidably mounted therein 25 by means of the flanges 23 fitting within the guide-ways 22. When it is desired to use the tray for the reception of letters, papers or the like it may be quickly and easily pulled forward into position over the front 30 part of the desk as shown in Fig. 1, and when not in active use it may be pushed rearwardly into an out of the way position on top of the desk as shown at the right hand side of Fig. 1. Also should it be de- 35 sired when collecting the letters, papers or the like from the basket the entire basket or tray may be removed by pulling the tray entirely out of the guide-ways 22, thus permitting the tray with its contents to be 40 filed away or transported to any place desired.

In order to prevent the tray being inadvertently entirely removed from the guide-ways when being pulled forward or pushed backward out of the way, I have provided 45 the stop means illustrated in Figs. 1, 2, 3, 4 and 6, which is described as follows. The blank from which the bottom portion 10 of the sliding tray is formed is provided with 50 the slits 31, 32 and 33. The metal between the slits 31 is pressed upwardly to form the elevated portion 30 shown in Fig. 6, and which elevated portion is provided with the perforation 36 for a purpose to be herein- 55 after pointed out. It is obvious, of course, that instead of providing slits 31 the elevated portion 30 could be formed by being pressed into shape without the use of slits if desired. It will be noticed that this elevated portion 30 is located adjacent the rear 60 end of the bottom 10. As seen in Fig. 10 the base portion 1 has punched therefrom and bent slightly upwardly the resilient tongues 37 and 38. The metal between the 65 slits 32 and 33 in the blank from which the

tray bottom 10 is formed is curved upwardly as indicated in Fig. 6 to form the tongues 39 and 40.

From this arrangement it will be seen 70 that the tray may be readily slid into position upon the base portion 1 by virtue of the fact that the tongues 39 and 40 will ride over and press downwardly the tongues 37 and 38 into flat position (see tongue 37 in Fig. 2). When the tray has been pulled out 75 over the top of the desk until the recess formed beneath the upstanding portion 30 comes into registry with the tongue 37 this tongue will, due to its resilient nature, be 80 free to rise upwardly at its free end into this recess and engage the shoulder 34 at the rear end of said recess. Due to the fact that the inclination of this tongue 37 is toward the front of the base portion the basket may be readily slid backward into 85 position shown on the right hand side of Fig. 1 when not in use, and during such rearward movement the tongue 37 will be again depressed by reason of the flat bottom 90 of the bottom portion 10 of the tray riding thereover.

When the tray has reached the position shown at the right in Fig. 1 the tongue 38 will then be in registry with the recess beneath the elevated portion 30, at which time 95 this tongue will snap upwardly and be in position to engage the shoulder 35 at the front edge of the recess, thus preventing the tray from being slid too far to the rear.

When it is desired to entirely remove the 100 tray from the base portion all that is necessary is to insert a pencil or the finger through the opening 36 and depress whichever tongue 37 or 38 is in registry therewith, after which the tray may be easily 105 entirely removed from the base portion.

Referring now to the means to make possible the adjustment of the base portion, to desk tops of varying widths, and referring to Figs. 9 to 12, it will be seen that 110 instead of stamping the tongues 5 from the base portion 1, I may provide at the front end of the base portion the clamping plate 41, which is slidably engaged between the guide-ways 42 and 43, formed by providing 115 suitable flanges to the underneath side of the base portion 1. Pressed from the metal of the base portion 1 and extending downwardly therefrom is the resilient tongue 44. At the rear end of the clamping plate 41 120 is provided the downwardly curved resilient tongue 45, while at the forward edge of this plate is the flange 46, by means of which the same may be manipulated. In the upper central line of the plate 41 is 125 provided a plurality of transverse slots 47, the rear edges of which are bent downwardly to form the projections 48. Any desired number of these slots may be provided, the essential requirement being that 130

these slots be sufficiently great in number, so that when the resilient tongue 45 has been pressed firmly against the forward edge of the desk top there will be slot 47 in appropriate position to permit the resilient tongue 44 to spring thereinto, and bear with its free end against one of the downwardly extending projections 48, whereby to thus firmly clamp the base portion in position upon the desk top as clearly seen in Fig. 9.

Referring to Fig. 13, it will be seen that my device may be readily adapted to a flat top desk by providing a simple cabinet structure indicated at 50 which may contain drawers, pigeon holes, or the like, the top portion 51, and be readily and easily secured in position upon the flat top desk by means of any desired member of clamps 52, or other suitable fastening means. This arrangement makes possible the sliding of my improved tray at a suitable height above an ordinary flat top desk when it is desired to use the same in connection therewith.

While I have illustrated my improved device as being formed from sheet metal, it is obvious that the same may be formed of any other suitable material without departing from the spirit of my invention.

Having now described my invention I claim:

1. In a desk tray, a base portion adapted to be attached to the upper portion of a desk, a paper-receiving tray slidably mounted in said base portion, means to prevent said tray being inadvertently slid entirely out of said base portion, and said means comprising a recess in one of said parts and a finger on the other of said parts, said finger adapted to enter said recess when registering therewith.

2. In a device of the class described, a base portion adapted to be attached to the upper portion of a desk and externally thereto, a paper-receiving tray slidably mounted in said base portion, said base portion and said tray having inter-engaging flanges serving as guideways, means to prevent said tray being inadvertently slid entirely out of said base portion, said means being operable to permit said tray to be removed from the base portion when desired and comprising a resilient tongue on the base portion to engage a recess in the bottom of the tray.

3. In a device of the class described, a base portion adapted to be attached to the upper portion of a desk, a paper-receiving tray slidably mounted in said base portion, said base portion being adjustable whereby to accommodate desks of different dimensions.

4. In a device of the class described, a base portion, guideways formed in said base portion, a tray having flanges slidably mounted in said guideways, stop means to

limit the sliding movement of said tray, said stop means being operable to permit the tray to be entirely withdrawn from said guideways, and means on said base portion to attach the same to the upper portion of 70 a desk, said last mentioned means being adjustable whereby to accommodate desks of different dimensions.

5. In a slidable desk tray a base portion, guideways formed in said base portion, a 75 fixed flange at one end of said base portion, and an adjustable flange adjacent its other end whereby said base portion may be adjusted to clamp over desks of varying dimensions.

6. In a desk tray a body portion having side walls, outwardly extending flanges on said side walls, a bottom portion having its edges bent up over said flanges, and a base portion having its longitudinal edges bent 85 upwardly and inwardly whereby to form opposed guideways to slidably receive certain of said bent over edges of said bottom portion.

7. In a device of the class described, a 90 base portion, a tray slidably mounted on said base portion, and resilient tongues carried by and depending from the lower side of said base portion and suitably spaced whereby to permit said tongues to grip over the top 95 edges of a desk to hold said base portion thereon.

8. In a device of the class described, a base portion having guideways thereon, a tray having overhanging means extending 100 laterally therefrom slidably engaging said guideways, a resilient stop on one of said parts and adapted to permit said tray to slide along said base portion until a predetermined position is reached, and means on 105 the other part to engage said stop when registering therewith to prevent withdrawal of said tray, said stop being releasable to permit complete withdrawal of said tray when desired.

9. In a device of the class described a base portion, a tray slidably mounted thereon, a flange at one end of said base portion adapted to take over one edge of a desk top, and a clamping plate adjacent the other end of said 115 base portion adapted to bind against the opposite edge of said desk top, and means co-operating between said base portion and said clamping plate whereby said plate may be adjusted to various positions to accommodate desk tops of different widths.

10. In a device of the class described a base portion, a tray slidably mounted thereon, a flange at one end of said base portion adapted to take over one edge of a desk top, and a clamping plate adjacent the other end of said base portion adapted to bind against the opposite edge of said desk top, and means co-operating between said base portion and said clamping plate whereby said plate 130

may be adjusted to various positions to accommodate desk tops of different widths, said means comprising a resilient tongue on one of said parts and a series of slots in the other 5 of said parts.

11. In a device of the class described, a base portion adapted to be attached to the upper portion of a desk, a paper-receiving tray slidably mounted in said base portion, 10 means to prevent said tray being inadvertently slid entirely out of said base portion, and said means comprising a recess in one of said parts and a pair of spaced resilient fingers on the other of said parts said fingers 15 adapted to respectively enter said recess when registering therewith.

12. In a device of the class described, a base portion adapted to be attached to the upper portion of a desk, a paper-receiving tray slidably mounted in said base portion, 20 means to prevent said tray being inadvertently slid entirely out of said base portion, and said means comprising a recess in one of said parts and a pair of spaced resilient 25 fingers on the other of said parts said fingers adapted to respectively enter said recess when registering therewith, and means per-

mitting either of said fingers to be removed from said slot when in engagement therewith to permit the tray to be entirely removed from said base portion. 30

13. In a device of the class described, a base portion adapted to be attached to the upper portion of a desk and externally thereto, a paper-receiving tray slidably mounted in said base portion, said base portion and said tray having interengaging flanges serving as guideways, means to prevent said tray from being inadvertently slid entirely out of said base portion, said means comprising a recess and a tongue and being operable to permit said tray to be removed from the base portion when desired, said recess comprising an indentation of the metal of the tray, and said indented metal 45 having an aperture therethrough permitting access to the tongue to operate same to release the tray for complete withdrawal.

In witness whereof I hereunto subscribe my name to this specification in the presence 50 of a witness.

ALBERT T. VAN ALSTYN.

Witness:

H. L. CHAPMAN.
